UNITED STATES PATENT OFFICE

MARVIN L. CHAPPELL, OF LOS ANGELES, CALIFORNIA, ASSIGNOR TO STANDARD OIL COMPANY OF CALIFORNIA, OF SAN FRANCISCO, CALIFORNIA, A CORPORATION OF DELAWARE

PROCESS OF PRODUCING HYDROCARBON PRODUCTS BY THE ACTION OF A METALLIC HALIDE AND A PARTIALLY CHLORINATED MINERAL OIL OF THE CARBO-CYCLIC SERIES

Application filed March 7, 1927. Serial No. 173,253.

This invention relates to the treatment of mineral oils, such as petroleum oil, with metallic halides, such as aluminum or ferric chloride.

5 In the conventional method of reaction upon petroleum oils by metallic halides, such as aluminum chloride, the petroleum oil and metallic halide admixture is heated to a temperature of from 300° to 600° F. Particularly when the process is carried out for the production of gasoline or motor fuel, a large percentage of the high boiling point unsaturated components of the petroleum oil are polymerized with the formation of tars. The 10 formation of such tars hinders, to a large extent, further reaction of the metallic halide on the oil and increases considerably the difficulty of securing proper contact with the metallic halide and the oil, thereby necessitating the employment of excessive amounts 15 of aluminum chloride to treat the oil or resulting in the production of a small yield of gasoline or motor fuel.

Furthermore, when hydrocarbon oil is subjected to the action of metallic halides for the purpose of refining the oil for the production, for example, of high grade lubricating oils, the unsaturated high boiling point hydrocarbons are also polymerized and are 20 difficult to separate from the lubricating oil stock and, moreover, both increase the difficulty of obtaining contact between the hydrocarbon oil and metallic halide and also hinder the further action of the metallic halide on 25 the oil by rendering said metallic halide less active.

I have discovered that this tar formation can be decreased and a higher percentage of motor fuel or refined oil produced by first 30 treating the mineral or petroleum oil to be processed with chlorine under conditions to form with the unsaturated compounds of the oil, a partially chlorinated or addition product. Such a reaction has been found to proceed when such mineral or petroleum oils are treated with chlorine at a temperature 35 ranging approximately from 60° to 212° F. Under such conditions, sufficient chlorine combines with the unsaturated oils of the 40 mineral oil body to form substantially satu-

rated chlorinated hydrocarbons. When such partially chlorinated mineral or petroleum is thereafter subjected to reaction with metallic halide, particularly in the presence of non-chlorinated compounds of saturated nature, 55 they may be refined to produce a high grade lubricating stock with a minimum production of tar and with great efficiency insofar as the consumption of aluminum chloride is concerned. 60

Moreover, when such partially chlorinated mineral or hydrocarbon oils are treated with a metallic halide, particularly in the presence of non-chlorinated saturated oil at temperatures ranging from 300° to 650° F., and 65 preferably under evolved pressure of about 20 pounds per square inch gage, a high yield of gasoline or motor fuel may be obtained with a low production of tar and a low consumption of metallic halide. 70

The present invention will be most clearly understood from a description of a preferred form or example of a process which embodies the invention. For this purpose, I have 75 hereinafter set forth an example of a process which embodies the invention. The process is described in connection with the accompanying drawing, which illustrates diagrammatically an apparatus suitable for conducting the process. 80

In the drawing:

The apparatus is indicated as in diagrammatic elevation and with certain parts in vertical section.

Referring to the drawing, 2 indicates a 85 reaction chamber preferably provided with some suitable heating means, being indicated as set over a furnace 3 provided with a burner 4. 5 indicates a line having a valve 6, which line may be employed for introducing mineral or petroleum oil into the reaction chamber 2. The reaction chamber 2 is also provided with a line 7 controlled by a valve 8 for introducing chlorine into the 90 reaction chamber 2, said line 7 preferably terminating within the reaction chamber 2 in a distributing line 9 by which the gaseous chlorine may be distributed or sprayed through the oil contents therein. The reaction chamber 2 is also preferably provided 95 100

with a vapor withdrawal line 10, controlled by a valve 11, by which means petroleum vapors and unreacted chlorine or other products may be withdrawn from the reaction chamber 2 as desired.

The reaction chamber 2 is indicated as connected by a line 12 including a pump 13 to a second reaction chamber 14. The reaction chamber 14 is indicated as provided 10 with an aluminum chloride charger 15 including the hopper 16 and spaced valves 17 and 18 by which solid metallic halide may be introduced into the reaction chamber against the pressure employed therein. The 15 charger is also indicated as provided with a valve controlled line 19 by which metallic halide in liquid form may be introduced if desired.

The reaction chamber 14 is preferably provided 20 with suitable heating means and for this purpose, is indicated as mounted over a furnace 20 having the burner 21. The reaction chamber 14 also preferably includes suitable means, such as the rotary agitator 22 25 for agitating the contents of the reaction chamber. 23 indicates a vapor line leading from the reaction chamber 14 to a dephlegmator or reflux tower 24.

The reflux tower 24 is provided at its lower 30 end with a line 25 which may be utilized for passing reflux or condensed materials either by line 26, controlled by valve 27, back into reaction chamber 14 or through line 28, controlled by valve 29 to a receiver 30. The receiver 30 is indicated as having a valve controlled draw-off line 31.

The dephlegmator 24 is preferably provided with a planer 32 having inlet and outlet passages 33 and 34 by means of which the 40 temperature of the vapors discharged from the dephlegmator may be controlled. If desired, the oil either in line 5 or in line 12 may be passed through this planer. The dephlegmator is connected with a vapor withdrawal line 35 leading through a condenser 36 to a receiving tank 37 for the gasoline or other low boiling point oil produced in the process. Said receiving tank 37 is provided with a valve controlled vent line 38 by means of which the pressure imposed upon the system may be controlled.

The reaction chamber 14 is also connected with a residual withdrawal line 39 controlled by a valve 40, which line leads to a receiver 41 55 having a valve control withdrawal line 42, which receiver may be employed to receive the spent metallic halide and sludge formed.

The process as carried out in the before described apparatus is preferably as follows:

As the feed oil of the system, any mineral 60 hydrocarbon oil may be employed, all of such oils containing unsaturated compounds of the carbo-cyclic series. The amount of chlorine fed into the reaction chamber 2 depends, of course, upon the amount of such unsaturated

constituents. Within the reaction chamber 2, the mineral hydrocarbon oil and chlorine which are continuously fed therein are maintained at a temperature ranging from approximately 60° to 212° F. and sufficient 70 chlorine is added to substantially combine with all of the unsaturated oils to form therefrom saturated chlorinated hydrocarbon compounds. The reaction is generally as indicated in the following equation, in which R indicates any hydrocarbon radical: 75

80

Upon certain mineral or hydrocarbon oils, a considerable portion of the chlorine fed into the reaction chamber 2 will not react with the oils upon a single passage through the body of oils and it is understood that the same is then merely recirculated through the body of the oil to secure efficient use of the chlorine. 85

The partially chlorinated mineral or hydrocarbon oil which always contains a quantity of saturated mineral or hydrocarbon compounds which have not been chlorinated is continuously passed into reaction chamber 14 in which chamber it is subjected to reaction with a metallic halide, preferably aluminum chloride. The temperature of the reaction in the reaction chamber 14 and the relative quantities of metallic halide and partially chlorinated mineral oil fed into the reaction chamber will depend upon the kind of reaction desired to effect in said reaction chamber. The process of the present invention is of advantage in case it is desired to produce refined lubricating oil stock or other refined viscous stock and is also of advantage when it is desired to conduct the metallic halide reaction to effect the catalytic decomposition of the oils into lower boiling point oils. In case a catalytic decomposition reaction is desired to be effected, the partially chlorinated mineral oil is heated in reaction chamber 14 to a temperature ranging from 300° to 650° F. The reaction is preferably conducted under a pressure above atmospheric, such as 20 pounds gage. As an example of suitable proportions of a metallic halide, such as aluminum chloride, I prefer to employ around 0.2 to 0.8 pounds of aluminum chloride per gallon of oil to be treated. 100 105 110 115

In case a lubricating stock only is desired, a smaller amount of the metallic halide or aluminum chloride is used and a lower temperature range is generally employed. For example, where it is desired to confine the reaction to produce mainly a refining action upon a viscous stock, I prefer to employ about 0.2 pounds of aluminum chloride per gallon of oil and to employ a temperature of about 212° F. In case a refined viscous stock only is being produced, this stock together with the residue formed in the evaporating cham- 120 125 130

ber 14 is generally conducted directly from the reaction chamber as a liquid through line 39 and passed into the receiver 41.

The reaction within the evaporating chamber 14 whether the process is carried out for the production of gasoline or for the production of a refined viscous stock, such as a refined lubricating oil stock, or for both, proceeds by the liberation of chlorine from the chlorinated or partially chlorinated mineral hydrocarbon compounds in the form of hydrogen chloride gas, the first reaction being as indicated by the following equation:

In case the higher temperatures are employed to produce motor fuel, a further reaction proceeds between the hydrocarbon formed and the metallic halide, such as indicated by the following equation:

The vapors evolved in the reaction chamber 14 are preferably passed to the dephlegmator 24 in which the motor fuel or naphtha is separated from the higher boiling point oils and passed from the dephlegmator together with the hydrogen chloride produced, the naphtha being condensed in the condenser 36 and collected in the receiving tank 37. The hydrogen chloride gas is withdrawn from the vent line 38 and, of course, may be recovered in any preferred or suitable manner.

40 The condensed high boiling point oils with or without some vaporized and condensed metallic halide may be passed either from the dephlegmator 24 to receiver 30 for a later separation or processing, or where it is desired to conduct the reaction to produce only naphtha or motor fuel and unrefined high boiling point oil, such condensed material from dephlegmator 24 may be passed to the evaporating chamber 14.

50 It will thus be seen that the process may be carried on mainly for the production of naphtha or mainly for the production of a refined viscous stock or for the simultaneous production of both naphtha and a refined viscous oil stock. In any case, the quantity of metallic halide necessary for such refining or decomposition is materially reduced over that required where the metallic halide is 55 contacted with a normal mineral hydrocarbon oil in place of the chlorinated or partially chlorinated oil employed in the present process.

60 It may be advantageous to employ pressures below atmospheric in certain cases, par-

ticularly when the process is being run for the production of lubricating stock.

70 While the process herein described is well adapted for carrying out the objects of the present invention, it is understood that numerous modifications may be made and all such modifications come within the scope of the following claim.

I claim:

75 A process of converting mineral oils of relatively high boiling point into motor fuels, while a part of the oils are simultaneously polymerized into refined viscous oils which comprises first contacting the same with chlorine at a temperature sufficient to chlorinate substantially only the unsaturated oils while separating the light petroleum vapors, and thereafter subjecting the liquid chlorinated mineral oils to reaction with a metallic halide at a temperature between 300° and 650° F., and at a pressure about seventy pounds per square inch above atmospheric.
